CONRAD JACOB BECHTEL, OF SANDUSKY, OHIO.

GRAPHITE-FEEDING DEVICE FOR ENGINES.

1,319,037.

Specification of Letters Patent. Patented Oct. 21, 1919.

Application filed July 24, 1918. Serial No. 246,520.

To all whom it may concern:

Be it known that I, CONRAD J. BECHTEL, a citizen of the United States, residing at Sandusky, in the county of Erie and State 5 of Ohio, have invented a new and useful Graphite-Feeding Device for Engines, of which the following is a specification.

This invention has reference to a graphite feeding device for engines, and is designed 10 to supply graphite to the valves and pistons of an engine in minute quantities whereby to smooth contacting surfaces, reduce friction and render the running of the engine easier and smoother.

15 The invention is applicable to both steam and explosion engines but for purposes of simplicity of description it will be considered that the device is applied to an explosion engine, and especially an explosion engine of the multi-cylinder type, without, however, limiting the use of the invention to such an engine or precluding its use in steam engines of either the single or multi-cylinder type.

20 The invention comprises a receptacle of relatively small size, capable of holding an ounce, more or less, of graphite in powdery form and especially the kind of graphite known commercially as fine flake graphite.

25 The receptacle is constructed for attachment to the intake manifold of a gas engine, say at or near the point where the manifold diverges to reach the cylinders. Associated with the receptacle is an elastically held

30 needle valve entering the outlet of the receptacle but at no time closing it, the arrangement being such that the valve is agitated by the suction of the engine and is so adjusted as to permit minute quantities of

35 graphite to flow through the intake valves into the cylinders, depositing upon the contacting surfaces of the valves and upon the walls of the cylinders where engaged by the pistons, this producing a good fit of the

40 valves and a smoothness of the cylinders contributing to the prevention of leakage past the pistons. The device is intended for occasional use, say once or twice a week in an explosion engine and at greater intervals

45 in a steam engine.

The invention will be best understood from a consideration of the following detailed description taken in connection with the accompanying drawing forming part of 50 this specification, with the understanding, however, that the invention is not confined

to any strict conformity with the showing of the drawing but may be changed and modified so long as such changes and modifications mark no material departure from 60 the salient features of the invention as expressed in the appended claims.

In the drawing:—

Figure 1 is an elevation of the device applied to the intake manifold of an explosion engine.

Fig. 2 is a longitudinal diametric section of the device on a larger scale than Fig. 1, with the valve in the quiescent state.

Fig. 3 is a view partly in section and 70 partly in elevation but showing the valve with the spring fully compressed.

Referring to the drawing, there is shown in Fig. 1 a portion of a manifold 1 which may be taken as indicative of the intake 75 manifold of any suitable type of explosion engine whether such manifold be of the particular shape indicated or some other appropriate shape.

For attachment to the manifold at or near 80 the point where the manifold branches to the different cylinders of the engine there is attached a cup 2 shown in the drawing as in the form of a cylinder with one end open and the other end closed by a head 3 which 85 may be made integral with the cylinder. Where the head 3 joins the cylinder 2 it is exteriorly of hexagon shape, as indicated at 4, for the application of a suitable tool such as a wrench, although it will be understood 90 that such particular shape is not obligatory. The head 3 is also formed with a nipple 5 which may be of exterior taper form to screw into a suitably threaded socket, the 95 taper form being a customary shape to permit a tight joint. Axially through the head 3 is a passage 6 of relatively small size and constituting a bore through the nipple 5. That end of the interior of the cylinder 2 located at the head 3 is tapered, as indicated 100 at 7, the taper leading into the passage or bore 6. Since the device is customarily used in an upright position fine graphite contained in the cylinder or cup 2 will readily gravitate to the bore 6 for escape 105 therethrough.

Applied to the open end of the cup 2, which is exteriorly threaded as indicated at 8, is a head or cap 9 interiorly screw-threaded to fit the threaded end 8 of the cup 2. 110 The cap 9 has an axially extended neck 10 of which one end 11 is interior to the cap.

and is contracted to form an annular shoulder 12. That portion of the neck 10 exterior to the head 9 terminates in screwthreads 13 for receiving a gland 14 for confining 5 packing 15 against the threaded end of the neck 10.

Extending axially through the gland 14, neck 10 and cup 2 is a stem 16 provided at the outer end with a head 17 and at the 10 other end tapering, as indicated at 18, and there entering the passage or bore 6. The stem 16 is provided with a collar 19 movable within the neck 10 and surrounding the stem between the collar 19 and the flange 12 15 is a coiled spring 20 so arranged as to normally hold the collar 19 against the packing 15, in which position the taper end or needle point 18 is within the bore 6. The diameter of the stem 16 is slightly less than 20 the diameter of the bore 6 so that the stem at its pointed or needle end may fully enter the bore 6 without completely filling it, it having been found in practice that a clearance of, say one-hundredth of an inch more 25 or less will answer.

The nipple end 5 of the head 3 may be screwed directly into the manifold 1 or it may be carried by a screw coupling 21 in turn carried by a short nipple 22, which latter is screwed into the manifold 1. In case 30 of a steam engine, where there is back pressure, the coupling 21 may be replaced by any suitable valve device which may be closed when found advisable. Such a valve device, 35 indicated at 23 in Fig. 3, may be used with the graphite holder when applied to an explosion engine, since it may be found advisable at times to cut off communication between the graphite holder and the interior of the manifold 1.

When the explosion engine is running, suction is produced by the piston in each cylinder and a few particles of the fine graphite are drawn into the manifold and 45 into the cylinder where the suction is produced. The result is that the graphite is distributed to each cylinder, passing first through the intake valve, wherefore, the contacting portions of the valves and their 50 seats become more or less coated with graphite and the walls of the cylinders and pistons also become coated with graphite. The effect of this is that carbon does not find lodgment on the valves and their seats where 55 contacting and carbon does not accumulate on the cylinder walls, wherefore, good compression and smooth running of the pistons is insured. This contributes materially to the running of the engine by reducing friction and leakage, and, consequently, greater power is obtained than heretofore. Since 60 the valves close tightly and the pistons run smoothly the reduction in friction and leakage results in a saving in fuel, which saving may be quite material.

While the valve stem 16 is agitated by the suction of the engine and usually the flow of graphite is uniform because of such agitation, sometimes a stoppage of the graphite might occur due to the packing of the 70 graphite, and, in such case, such stoppage may be remedied by pressing on the head 17 to move the needle end 18 of the valve deep into the passage 6, as shown in Fig. 3.

At suitable intervals, say once or twice 75 a week in the case of an explosion engine and at longer intervals in case of a steam engine, the cup or receptacle 2 is filled with graphite, preferably fine flake graphite, by removing the head or cap 9. Then on re- 80 storing the cap 9 to its place on the cup 2 the device is ready for operation. By the time an explosion engine has been run for a few minutes, say fifteen or twenty minutes, the cup or receptacle 2 is emptied and 85 the graphite is distributed over the intake valves, over the interior of the engine cylinders and also over the contacting faces of the exhaust valves. The supply of graphite so deposited will answer for a considerable 90 period of time, varying with the use of the engine, and experience will show how often there should be applications of graphite to keep the engine in perfect running condition.

The invention has still other advantages 95 in that the lubricating qualities of the graphite prevent wear that frequently occurs in explosion engines in the absence of the graphite and consequently the life of 100 the engine is correspondingly prolonged, and the amount of lubricating oil required is greatly reduced. Also, the graphite keeps the spark plugs clean and renders the use of kerosene as a fuel more successful than 105 when the graphite is not provided.

What is claimed is:—

1. The combination with the fluid intake of an engine, of means for the application of graphite to the valves and cylinders of 110 the engine, comprising a receptacle for the graphite attached to the intake and provided with an outlet passage leading to the intake, and a stem with a tapering end incompletely closing the outlet passage of the receptacle 115 and elastically yieldable to the suction of the engine, said stem and outlet being proportioned to permit minute quantities of graphite to escape from the receptacle under the suction of the engine.

2. A device for feeding graphite to the valves and cylinders of an engine, comprising a cup or receptacle having one end provided with a reduced outlet passage and otherwise closed, a removable head for the 125 other end of the receptacle, said head having a neck extending into and out of the receptacle with the inner end of the neck reduced in diameter, a packing gland at the outer end of the neck, a valve stem extending through 130

the packing gland and neck and also through the receptacle and entering the outlet of the receptacle with the stem of less diameter than said outlet, and a spring in the neck surrounding the stem and normally tending to hold the stem at one limit of its travel, said stem being capable of reciprocation within the outlet of the receptacle.

5 3. A device for feeding graphite to the valves and cylinders of an engine, comprising a cup or receptacle having one end provided with a reduced outlet passage and otherwise closed, a removable head for the other end of the receptacle, said head having a neck extending into and out of the receptacle with the inner end of the neck reduced in diameter, a packing gland at the outer end of the neck, a valve stem extending through the packing gland and neck and also through the receptacle and entering the outlet of the receptacle with the stem of less diameter than said outlet, and a spring in the neck surrounding the stem and normally tending to hold the stem at one limit of its travel, said stem being capable of reciprocation within the outlet of the receptacle, and where entering the outlet being of tapered or needle valve construction.

10 4. A device for feeding graphite to the valves and cylinders of an engine, comprising a cup or receptacle having one end provided with a reduced outlet passage and otherwise closed, a removable head for the other end of the receptacle, said head having a neck extending into and out of the receptacle with the inner end of the neck reduced in diameter, a packing gland at the outer end of the neck, a valve stem extending through the packing gland and neck and also through the receptacle and entering the outlet of the receptacle with the stem of less diameter than said outlet, and a spring in the neck surrounding the stem and normally tending to hold the stem at one limit of its travel, said stem being capable of reciprocating within the outlet of the receptacle, and where entering the outlet being of tapered or needle valve construction.

15 5. A device for feeding graphite to the valves and cylinders of an engine, comprising a receptacle with means for attaching it to the engine and having an outlet bore or passage for directing the graphite into the engine, and a reciprocatory elastically mounted stem traversing the receptacle and entering the outlet passage with said stem at the outlet passage being of progressively less diameter than said passage in the direction of entrance thereinto so as to move into the passage without closing but progressively reducing the latter, whereby the valve may be reciprocated in the outlet passage without at any time fully closing the latter and at all times permitting the escape of minute quantities of graphite from the receptacle under the action of the engine.

20 6. A device for feeding graphite to the valves and cylinders of an engine, comprising a receptacle with means for attaching it to the engine and having an outlet bore or passage for directing the graphite into the engine, and a reciprocatory elastically mounted stem traversing the receptacle and entering the outlet passage with said stem at the outlet passage being of progressively less diameter than said passage in the direction of entrance thereinto so as to move into the passage without closing but progressively reducing the latter, whereby the stem may be reciprocated in the outlet passage without at any time fully closing the latter and at all times permitting the escape of minute quantities of graphite from the receptacle under the action of the engine, said stem having a range of travel in excess of its reciprocatory travel under the action of the engine for clearing the outlet passage in the event of the latter being choked.

25 7. A device for feeding graphite to the valves and cylinders of an engine, comprising a receptacle with means for attaching it to the engine and having an outlet bore or passage for directing the graphite into the engine, and a reciprocatory elastically mounted stem traversing the receptacle and entering the outlet passage with said stem at the outlet passage being of progressively less diameter than said passage in the direction of entrance thereinto so as to move into the passage without closing but progressively reducing the latter, whereby the stem may be reciprocated in the outlet passage without at any time fully closing the latter and at all times permitting the escape of minute quantities of graphite from the receptacle under the action of the engine, said stem having a range of travel in excess of its reciprocatory travel under the action of the engine for clearing the outlet passage in the event of the latter being choked.

In testimony that I claim the foregoing as my own, I have hereto affixed my signature.
